UNITED STATES PATENT OFFICE.

JOSHUA STRUTHERS, OF FRANKLIN, PENNSYLVANIA.

DEVICE FOR CONTROLLING GENERATORS.

No. 815,129.

Specification of Letters Patent.

Patented March 13, 1906.

Application filed September 12, 1904. Serial No. 224,145.

To all whom it may concern:

Be it known that I, JOSHUA STRUTHERS, a citizen of the United States of America, residing at Franklin, in the county of Venango 5 and State of Pennsylvania, have invented certain new and useful Improvements in Devices for Controlling Generators, of which the following is a specification, reference being had therein to the accompanying drawing.

This invention relates to certain new and useful improvements in devices for controlling generators; and the invention has for its object the provision of novel means whereby the speed of the armature-shaft may be easily 15 controlled and limited.

Another object of this invention is to provide novel means in connection with the armature-shaft of generators or motors whereby when the shafts have revolved to a predetermined speed the excess speed of the armature-shaft may be employed for stopping the further movement of the controller-handle in a direction which would increase the current supplied to the motor and operating-brakes 25 that may be used in connection with my improved device.

With the above and other objects in view the invention consists in the novel construction, combination, and arrangement of parts 30 to be hereinafter more fully described.

In describing the invention in detail reference is had to the accompanying drawing, forming a part of this application, in which the single figure is a diagrammatical view of 35 my improved device when used in connection with armature-shafts of motors for street-cars and like vehicles.

In the drawing I have illustrated what may be termed a "mechanical" governor for 40 controlling the current and for operating air-brakes in connection with the armature-shaft of an electric motor, the governor being of the type commonly known as the "inverted" governor, wherein the centrifugal force of the 45 balls is resisted by a spring around the spindle and the extension of the balls lifts the lever-spool through a toggle-joint movement. The reference character N indicates the armature, and O the shaft. P designates the 50 commutator, and Q R the brush-holders. A governor 8 is secured upon the shaft O and is connected to a lever-spool 9, which engages the lever 10, pivotally mounted in the extension 11 of the armature brush-holder R. In 55 connection with the armature N, I have illustrated diagrammatically a controller S, which

is operated by a lever T. The brush-holder R is connected by a wire 12 to mechanism contained within the controller, and said mechanism is connected by wires 14 to a variable resistance 15, from which the wire 16 leads to the "load," another wire 17 leading from said armature brush-holder Q to the same load. The reference-numeral 18 designates a lever which is pivotally connected to the lever 10, and this lever is adapted to control the stop which is employed in connection with the controller, this stop being placed in a suitable position whereby it will interrupt the movement of the lever T and prevent said lever from being further rotated in the direction in which current is turned on by the movement of said lever and a higher speed obtained. In the present illustration I have constructed a pivoted lever 19 upon 60 the casing of the controller, and as the speed of the armature-shaft increases and the lever-spool is raised by the centrifugal motion of the balls the lever 18 will be forced downwardly, which will carry with it the outer end 70 of the lever 19, throwing the other end upwardly to obstruct the path of travel of the controller-lever T.

My improved device is further used for controlling air-brakes, and is particularly 85 used in connection with street-cars. The lever 10 carries a pin 20, which engages in the slotted end of a bar 21, that is connected to the lever 22 of the air-brake system commonly carried by street-cars and other electrical vehicles. The device as illustrated in the drawing is so constructed that when the armature-shaft has reached such a speed that the armature is liable to be "burned out" the lever 19 will be thrown into such position that the controller cannot be moved past said lever 19, which will prevent the motorman from further increasing the speed, and should the street-car be traveling at this speed and an incline reached that is to be descended the 90 increased rapidity of the car will cause the governor to operate the lever 10 and open the valve of the air-brake system to throw on the brakes.

Having fully described my invention, what 105 I claim as new, and desire to secure by Letters Patent, is—

1. In apparatus of the character described, the combination of an electric motor, a governor operatively connected to the shaft of 110 said motor, a controller, a rotary shaft mounted in said controller, handle mounted

on said shaft, a stop mounted on said controller and adapted to engage said handle, electrical connections between said motor and said controller, and mechanism connecting 5 said governor and said stop whereby the movement of the governor will operate said stop to limit the movement of the controller.

2. In apparatus of the character described the combination of an electric motor, a governor operatively connected to the shaft of 10 said motor, a controller, a rotary shaft mounted in said controller, a handle mounted on said shaft, a stop mounted on said controller and adapted to engage said handle, electrical connections between said motor and 15 said controller, and mechanism connecting said governor and said stop whereby the movement of the governor will operate said stop to limit the movement of the controller- 20 shaft, an air-brake valve, connections between said air-brake valve and said governor whereby the movement of the governor will operate said air-brake valve.

3. In an apparatus of the character de- 25 scribed, the combination with a car and an electric motor mounted on the car, of a governor mounted on the car and receiving motion from said motor, a controller mounted on the car and in circuit with said motor, 30 means connected with said governor for stopping the shaft of the controller against movement in one direction when the motor has reached a predetermined speed, braking mech-

anism mounted on the car and means operated by said governor for operating said braking mechanism after the movement of the controller-shaft has been stopped. 35

4. In apparatus of the character described, the combination with an electric motor, a governor operated by said motor, a controller, a rotary shaft by means of which the controller is operated to increase or diminish the current passing through said motor, of means connected to and operated by the said governor for mechanically interrupting the 40 movement of said shaft and thereby preventing an increase of the current supplied to the armature when the speed of the same has reached a predetermined limit. 45

5. In an apparatus of the character de- 50 scribed, the combination with a car, an electric motor mounted on the car, a governor mounted on the car and operatively connected to the armature-shaft of said motor, a controller mounted on the car, means whereby 55 when the armature has reached a predetermined speed the shaft of the controller will be stopped against further movement in a direction tending to increase the input of current to the motor.

In testimony whereof I affix my signature in the presence of two witnesses.

JOSHUA STRUTHERS.
